UNITED STATES PATENT OFFICE.

JOSEPH A. McELROY, OF NEW YORK, N. Y.

SPRINKLER HEAD.

Application filed February 28, 1922. Serial No. 539,821.

To all whom it may concern:

Be it known that I, JOSEPH A. McELROY, a citizen of the United States, and resident of New York, in the county of New York and State of New York, have invented certain new and useful Improvements in Sprinkler Heads, of which the following is a specification.

This invention relates to sprinkler heads such, for example, as are used in automatic fire extinguishing systems of the kind in which a valve is held over an outlet by means of a strut interposed between the valve and an opposed abutment.

One object of my invention is to provide a device of cheap and simple construction and one which may readily be assembled. A further object is to provide a device in which the number of component parts is reduced to a minimum.

My invention will be best understood by reference to the accompanying drawings illustrating preferred embodiments thereof, wherein like numerals refer to like parts throughout and in which:

Fig. 1 is a front elevation of a sprinkler head embodying my invention.

Fig. 2 is a vertical sectional view looking from the left in Fig. 1, the strut being shown in elevation.

Fig. 3 shows a portion of one member of the toggle forming the strut shown in Fig. 2.

Fig. 4 is a transverse vertical sectional view of the strut shown in Figures 3 and 5.

Fig. 5 is a plan view of that portion of the toggle device shown in elevation in Fig. 3.

Figs. 6 and 7 are a section and elevation respectively of one member of a fusible link embodying a modified form of my invention.

Fig. 8 is a fragmental view of a sprinkler head equipped with a fusible link embodying the modification shown in Figures 6 and 7.

Fig. 9 is a side elevation partly in section of the device illustrated in Fig. 8.

I have herein disclosed my invention as applied to a sprinkler head of the usual type wherein a hollow hub 1, provided with a nipple 7 adapted to engage a socket in a water supply system, has two arms 2, 3 cast integral therewith, said arms terminating in a boss 4. The boss 4 is provided with a de-

flector 5 of the usual type and is internally threaded to receive an adjusting screw 6.

A valve cap 8 is seated upon the outlet of 55 the fitting and is held in position by means of a strut.

In Figs. 1 and 2 of the drawings, I have illustrated the strut as composed of two bell crank levers which have the substantially counterpart arms 9 and 10 respectively, pivotally engaging valve and adjusting screw respectively and having a pivotal engagement with each other. The point of bearing between the two arms is offset from 60 the line of stress between the points of bearing on the valve and screw so as to form a partially broken toggle and the pressure thereon of the valve and the adjustment screw tend to further break the toggle. To 65 maintain the toggle against any fluid pressure which may be behind the valve, the levers have other arms 11 and 12 extending laterally therefrom. In one form of my invention the arms 11 and 12 are formed with 70 substantially flat portions 13 extending in a plane substantially parallel with the plane including the arms of the lever and so arranged that when the levers are in their operative position the flat portions 13 lie 75 adjacent one another or coincide. The portions 13 are formed on their inner or adjacent faces with grooves or depressions 14 and these depressions in the embodiment illustrated take the form of a cross, the arms 80 of which are illustrated as being at right angles to each other although it is obvious that any system of grooves may be used in which arms or channels radiate from a common center. As will be obvious from an inspection of Fig. 2, the grooves on the adjacent faces do not coincide but are so arranged that the grooves on one face come 85 opposite the space between the grooves on the adjacent face. The parts 13 normally 90 are held together by a readily fusible solder 95 which fills the grooves 14 and extends between the adjacent faces. The solder filling the grooves in the adjacent faces forms a mass sufficient to overcome any tendency to 100 "cold flow" and prevents any displacement in the relative positions of the two faces. The two bell crank levers are assembled as shown in Fig. 2 with the adjacent faces of

the portions 13 held together by a readily fusible solder 15 interposed therebetween to form a toggle or strut which is inserted in the sprinkler head in the usual manner between the valve and the adjustment screw 6. It will be observed that the common centers from which the grooves run on the respective faces or plates substantially coincide while the grooves in one face do not register with the grooves in the proximate face. Centrally of the plates, however, there are depressions formed which do register and these depressions when filled with solder result in the formation (in the illustrated embodiment) of an eight-pointed star of substantial thickness. The radiating points of this star-shaped mass of solder 14* resist the shearing moments impressed thereon by the constant tendency of the arms 11 and 12 to separate under the toggle action of the arms 9 and 10 until the surrounding temperature is raised sufficiently to melt the solder. The screw is then turned to force the toggle against the valve until the desired stress is exerted to hold the valve against fluid pressure in the supply system.

In Figs. 6 to 9 I have disclosed a modification of my invention in which the bell crank levers are so constructed that when the two levers are assembled in their operative position the arms 11' and 12' diverge to form an angle of sufficient magnitude to permit the use of a fusible connection between the effective ends as clearly disclosed in Fig. 9. The ends of the arms 11' and 12' are shaped to form hooks 18 and the link which I have designated in its entirety as 25 is provided near its opposite ends with slots 24 adapted to engage the hooks and maintain the levers in their operative position.

The link 25 comprises the co-operating plates 16 and 17. Each plate is provided with an aperture 24 and upon one face of the link a groove 14' is provided. I prefer that this groove be in the shape of a cross or similar shape in which a plurality of arms radiate from a common center. Each pair of plates are so arranged that when assembled the slots 24 will be diametrically opposed to one another and so that the grooves will not coincide, but so that the grooves on one plate will lie adjacent that portion of the face of the juxtaposed plate which lies between the grooves on that plate.

In assembling the link two co-operative parts 16 and 17 are placed side by side with the faces containing the grooves adjacent one another and with the central portion of the grooves from which the arms radiate opposite each other. A lump of readily fusible solder is placed in one of the depressions and the whole heated so that the solder fills the grooves and flowing over the adjacent faces binds the two parts together. A star-shaped mass of solder 14'* is formed at

the center as in the previously described modification and functions similarly to resist shearing stresses.

Having thus described in detail my invention as applied to the particular types of struts chosen for illustration in the drawings as an example, what I claim as new and desire to secure by Letters Patent is:—

1. The herein described tension device for sprinkler heads, the same comprising a pair of levers each having one arm provided with an enlarged portion, each enlarged portion having a plurality of depressions radiating from a common center, and a solder fusible at a predetermined temperature, filling said depressions and normally holding said enlarged portions together. 75

2. In an automatic sprinkler, a valve cap, a strut bearing upon said valve cap, said strut comprising two levers, one arm of each of said levers having an enlarged portion, each enlarged portion having a flat face provided with a plurality of depressions radiating from a common center, said flat faces being normally juxtaposed and secured together by a solder entering the depressions. 85

3. In an automatic sprinkler, the combination with a valve and valve cap therefor, of a strut comprising two levers, a plate carried with an arm of each lever respectively, a groove formed in each of the proximate faces of said plates respectively, the axes of said grooves being disposed at an angle to each other when the levers are in assembled relation whereby the grooves of one face oppose the plane face of the adjacent plate and the grooved faces being normally secured together by a solder fusible at a predetermined temperature. 90

4. In an automatic sprinkler, the combination with a valve and valve cap therefor, of a strut comprising two levers, a plate carried with an arm of each lever respectively, a plurality of grooves formed in each of the adjacent faces of said plates respectively, the axes of the grooves in one of the adjacent faces being disposed in angular relation to the axes of the grooves in the other of said adjacent faces when said plates are in assembled relation whereby the grooves of one face are disposed adjacent plane portions of the adjacent plate, said faces being normally secured together by a solder interposed therebetween. 105

5. In an automatic sprinkler, the combination with a valve and valve cap therefor, of a strut comprising two levers, a plate carried with an arm of each lever respectively, adjacent faces of said plates having formed therein a plurality of grooves radiating from a common center, the axes of the grooves formed in one of the adjacent faces being disposed at an angle to the axes of the grooves formed in the other of said adjacent faces when said plates are in assembled rela- 110

tion whereby the grooves of one face are disposed adjacent plane portions of the adjacent plate, said grooved faces being normally secured together by a solder interposed therebetween.

5. 6. In an automatic sprinkler, the combination with a valve cap of a strut comprising two levers, plates formed on an arm of said levers respectively, said plates being provided upon adjacent faces with a plurality of grooves radiating from a common center, the axes of the grooves formed in the respective faces being disposed at an angle to each other, said grooved faces being normally secured together by a solder interposed therebetween and filling said grooves.
- 10 15

7. In an automatic sprinkler, the combina-

tion with a valve cap, of a strut bearing upon said valve cap, said strut comprising two levers, one arm of each of said levers being formed with an enlarged portion, each enlarged portion having a flat face formed with a plurality of grooves crossing one another at right angles, the axes of the grooves on the respective faces being, when assembled, disposed at an angle to each other, said adjacent faces being normally secured together by a solder entering the depressions and fusible at a predetermined relatively low temperature.

Signed at New York in the county of New York and State of New York, February A. D. 1922.

JOSEPH A. McELROY.
